TREATMENT OF HYDROCARBON OILS

Original Filed June 6, 1931

UNITED STATES PATENT OFFICE

2,066,097

TREATMENT OF HYDROCARBON OILS

John Cutter, Tulsa, Okla., assignor, by mesne assignments, to Universal Oil Products Company, Chicago, Ill., a corporation of Delaware

Application June 6, 1931, Serial No. 542,534
Renewed March 23, 1935

2 Claims. (Cl. 196—48)

This invention relates to the treatment of hydrocarbon oils and refers more particularly to a method for topping and cracking oils simultaneously so as to produce motor fuel and other products.

The practice of my invention features the production of cracked and uncracked products direct from the process having substantially the boiling point characteristics of the finished products, and operating economies in the production of same.

In the specific embodiment of the invention, cracked vapors from the reaction zone are separated into motor fuel-containing vapors and insufficiently cracked hydrocarbons which are to be further converted; the motor fuel-containing vapors are reheated in the fractionator in which they were separated and then directed to further fractionating means where motor fuel is separated from relatively light intermediate hydrocarbons, then condensed and collected; hydrocarbon oil containing relatively lighter boiling components to be removed by distillation before cracking is preheated indirectly by products from the process undergoing condensation, is further heated indirectly in the fractionators of the cracking system; is then subjected to vaporization, the vapors fractionated and the non-vaporized portion of the hydrocarbon oil directed to cracking treatment.

Reference to the accompanying drawing, which illustrates in a diagrammatic manner one embodiment of the invention, will develop the features of the invention. Crude oil is charged to the process through line 1 and valve 2 to pump 3 which pumps the oil through line 4 and valve 5 to the heat exchanger 6, where the oil is preheated and then flows through line 8 regulated by valve 9 into the coil 10 disposed in fractionator 11. Any desired portion of this oil may by-pass coil 10 by passing through line 12 regulated by valve 13 and then to line 14. The oil from line 14 passes into line 15 regulated by valve 19 and may flow through coil 16 disposed in fractionator 17 and the heated oil directed through line 18 and valve 100 into line 19. Any portion of the oil flowing into line 15 may by-pass the coil 16 by flowing through valve 20 into line 19. Oil flowing through line 19 is directed to the vaporizer 21 where vaporization takes place and non-vaporized heavy hydrocarbons comprising the charging stock to the cracking process is separated from the lighter hydrocarbon components. The hydrocarbon vapors leaving the vaporizer through line 22 flows to the fractionator 23 where a heavy distillate cut such as furnace oil is separated out by fractionation. The fractionated vapors leave fractionator 23 through line 24 and flow to fractionator 25 where a distillate cut such as kerosene or heavy naphtha may be separated out. Vapors of the

character of motor fuel flow through line 26 to the condenser 27 and the cooled and condensed products flow through line 28 into separator 29 where the motor fuel may be removed through line 30 regulated by valve 31 and uncondensable products removed through line 32 regulated by valve 33. The fraction condensed and separated in fractionator 25 is removed through line 34, directed to cooler 35 and removed through line 36 regulated by valve 37 to suitable disposal. The fraction condensed in fractionator 23 is removed through line 38 to cooler 39 and the product discharged through line 40 regulated by valve 41 to suitable disposal.

Non-vaporizing charging oil separated in vaporizer 21 is removed through line 42 regulated by valve 43 and directed to pump 44 which pumps this oil through line 45 and valve 46 into line 47, which in turn discharges through valve 48 into line 49 leading to the heating element. 15 Reflux condensate formed in the fractionator 17 is removed through line 50 regulated by valve 51 and directed to pump 52 which pumps the oil into line 49 regulated by valve 53 and to the heating element 54 located in suitable furnace 55. Hydro- 20 carbon oil for cracking may also be directed into the oil flowing to the heating element by introducing same into the line 56 regulated by valve 57 leading to pump 58 which pumps said oil through line 59 regulated by valve 60 into line 30 25 47, which in turn discharges into line 49 leading to the heating element. The oil flowing through the heating element 54 is heated to a suitable cracking temperature under suitable pressure and discharged through line 61 regulated by valve 63 into reaction chamber 64 where oil undergoes conversion and non-vaporized residue is separated from vaporized products. Non-vaporized residue may be removed through line 65 regulated by valve 66, and vaporized products may be removed through line 67 regulated by valve 68 and directed to fractionator 17.

The character of the vapors leaving fractionator 17 may be regulated by the amount of oil directed through the coil 16 previously described. 45 These vapors are withdrawn through line 69 regulated by valve 70 and may then be reheated in the coil 71 by directing into line 72 regulated by valve 73 and returning through line 74 and valve 75 into line 69. Any portion of the oil or all of it may by-pass this coil and flow through valve 76 and the oil vapors heated in coil 71 disposed in the lower portion of fractionator 17. The vapors flow into coil 77 through line 78 regulated by valve 79 and leave the coil through line 50 55 80 regulated by valve 81 returning to line 69. Line 69 enters near the bottom of fractionator 11 wherein the vapors corresponding to motor fuel are separated from higher boiling insufficiently cracked constituents. The character of 60

the motor fuel product leaving fractionator 11 may be controlled by the oil flowing through coil 10 previously described. Heavier constituents condensed in fractionator 11 are removed through line 101 leading to cooler 83 and the cooled oil flowing through line 84 may be directed in part through line 85 regulated by valve 86 and directed to the top of fractionator 17 for cooling purposes.

10 Oil flowing through valve 87 may be removed from the process or if desired may be processed in a manner not illustrated, as for example the oil withdrawn through line 101 may be directed with or without cooling to further cracking treatment. Fractionated vapors leaving the top of fractionator 11 flow through line 88 regulated by valve 89 to heat exchanger 6 where they are cooled or condensed by indirect contact with crude oil flowing to the process. Cooled and condensed vapors flow through line 90 to cooler 91 where the products are further cooled and thence directed through line 92 and valve 93 to receiver 94 where separation of liquid and gaseous products is effected. Liquid products are removed 20 through line 95 regulated by valve 96 and gaseous or uncondensed products are removed through line 97 regulated by valve 98.

Temperatures employed in the process range from those required to heat the crude oil and remove by vaporization the various distillation products to those required to crack the topped crude oil and obtain suitable yields and character of cracked products. The cracking temperatures used may vary from 750° F., to 1000° F., or more, and the corresponding pressures may vary from low superatmospheric pressure of 50 pounds per square inch, more or less, to 2000 pounds per square inch or more. The pressures employed may be equalized between the various elements comprising the cracking process or differential pressures may be employed. For example, the pressure on the heating element 54, reaction chamber 64 and fractionator 11 may be equalized, the pressure on each varying only as a result of pressure drop through preceding elements, and the pressure reduced in the line between fractionator 17 and fractionator 11; or the pressure on the heating element 54 may be maintained at a given pressure, for example 350 pounds per square inch, by the regulation of valve 63, the pressure on the reaction chamber 64 and fractionator 17 may be maintained at approximately 200 pounds per square inch pressure by manipulation of valve 70 for example, and subsequent elements may be maintained at lower desired pressures.

As a specific example of the results obtainable in one operation of the process of my invention, a Mid-Continent crude oil of approximately 22° A. P. I. gravity is directed to the process and heated in indirect heat exchange with heated materials in the process as above described and approximately ten percent of gasoline of approximately 50° A. P. I. gravity removed from receiver 29, approximately 4 percent of kerosene of 40-42° A. P. I. gravity removed through line 36, and approximately 5 percent of 38-40° A. P. I. gravity removed through line 40. The topped crude oil is removed from vaporizer 21 by means of pump 44 and directed to the heating element together with reflux condensate from fractiona-

tor 17, where the oil is heated to approximately 900° F., at a pressure of approximately 200 pounds per square inch. Vapors leaving fractionator 17 at approximately 560° F. are reheated partly in coil 71 and partly in coil 77 so that the oil vapors entering fractionator 11 are about 620° F. The yield of motor fuel of approximately 400° F. endpoint is approximately 60 percent by volume of the topped crude, the remaining products from cracking comprising a heavy distillate removed from the bottom of fractionator 11, coke and gas.

The above example is only illustrative of one mode of operation of the improvements constituting the process of my invention and should not be construed as a limitation thereof.

I claim as my invention:

1. A hydrocarbon oil cracking process which comprises heating the oil to cracking temperature in a heating zone and separating the same into vapors and residue, introducing the vapors to a fractionating zone and fractionating the same therein to condense insufficiently cracked fractions thereof, removing uncondensed vapors from the upper portion of the fractionating zone and reheating the same by indirect heat exchange with the hotter hydrocarbons in the lower portion of the fractionating zone, further fractionating the reheated vapors to condense heavier portions thereof, introducing such condensed heavier portions into direct contact with the vapors undergoing fractionation in the fractionating zone, returning reflux condensate from the fractionating zone to the heating zone, and finally condensing the fractionated vapors.

2. A simultaneous distilling and cracking operation which comprises forcing a stream of crude oil through a closed zone in indirect contact with vapors from a fractionating zone whereby to preheat said crude oil and cool said vapors, passing said preheated stream of crude oil through a second closed zone in indirect contact with vapors being subjected to fractionation in said fractionating zone, whereby to further preheat said crude oil and partially condense said vapors to form reflux condensate, discharging said preheated crude oil in a separating zone where vapors separate from topped crude, subjecting said topped crude to cracking conditions of temperature and superatmospheric pressure in a cracking zone to form vapors and non-volatile residue, introducing the vapors to said fractionating zone and subjecting the same therein to fractionation by indirect contact with said closed stream of previously preheated crude oil, removing vapors remaining uncondensed after passage through said fractionating zone after said fractionation and passing the same in a closed stream in indirect contact with the vapors in said fractionating zone whereby to heat the vapors in the closed stream and partially condense the vapors being fractionated, further passing the heated vapors in indirect contact with said stream of crude oil in said first mentioned closed zone, introducing resultant reflux condensate into direct contact with the vapors in said fractionating zone, and condensing and collecting said vapors as a distillate product of the process.

JOHN CUTTER. 70
